UNITED STATES PATENT OFFICE.

HENRY J. CHILTON, OF CHICAGO, ILLINOIS.

BAG FITTING.

Application filed December 3, 1920. Serial No. 428,053.

To all whom it may concern:

Be it known that I, HENRY J. CHILTON, a citizen of the United States, residing at Chicago, in the county of Cook and State 5 of Illinois, have invented a certain new and useful Improvement in Bag Fittings, of which the following is a full, clear, concise, and exact description, reference being had to the accompanying drawings, forming a 10 part of this specification.

The invention relates to fittings for traveling bags, and other similar articles, and is primarily designed to provide a structure whereby the handle may be readily attached 15 to the frame of the bag.

One object of the invention is to provide a structure which will permit the attachment of the handle to the bag frame regardless of the distance between the means 20 usually provided in the frame for the attachment of a handle thereto. This means is usually a pair or a number of perforations provided in the frame, and consequently the means whereby the handle is attached to the frame must correspond to the 25 distance between these apertures, and as this distance varies in different frames, the application of a handle by means of a fitting which is of a fixed dimension eliminates it 30 as a means for attaching the handle to various frames and demands a special fitting for each frame.

The invention is particularly adapted for use in connection with a device such as shown 35 in the patent issued to me, in which a fitting is shown whereby the handle may be arranged interiorly and exteriorly of the bag and locked in these positions.

The invention will herein be explained in 40 connection with this structure. However, it is not so limited as it is applicable to other structures as well.

An added object of the invention is to provide a structure whereby a merchant may 45 readily substitute a fitting such as just described for the fitting usually provided upon the bag, without compelling him to punch another aperture in the frame or to keep on hand several fittings of various sizes in order 50 to substitute one fitting for the other.

It is a further object of the invention to provide a structure whereby one part may be centered with relation to the other part so that the device will not depreciate the 55 appearance of the bag when attached.

In addition it is an object to provide an

arrangement whereby the portion which permits the handle to be arranged interiorly and exteriorly of the bag is positively held in one of its positions, preferably when the 60 handle is arranged exteriorly of the bag, so that a force must be exerted thereon to release and allow it to be arranged within the bag.

The invention will be explained in conjunction with the accompanying drawings, 65 which illustrate various embodiments of the same, from which it is evident that various arrangements may be resorted to without departing from the spirit of the appended 70 claims forming a part hereof.

In the drawings Fig. 1 is a perspective view of a bag frame and handle having the invention applied thereto.

Fig. 2 is a longitudinal section. 75

Fig. 3 is a section on line 3—3 of Fig. 2.

Fig. 4 is a longitudinal section of a modified structure which may be resorted to.

Fig. 5 is a section taken on line 5—5 of Fig. 4. 80

Fig. 6 is a longitudinal section of another modified structure, and

Fig. 7 is an end view of the fastening element employed in conjunction with the structure shown in Fig. 4. 85

As before stated the invention is herein explained in conjunction with a fitting whereby the handle may be arranged interiorly or exteriorly of the bag. This fitting is composed of a pair of arms 10 and 90 11 which are spaced apart from each other and have the hinged element 12 arranged between them. This element is pivoted upon the pivot pin 13 and has one end of the handle 14 connected thereto. These arms 95 10 and 11 terminate at their uppermost ends in the laterally projecting portions 16, which are arranged adjacent the bag frame and connected thereto by means of the elements 17 which are passed through the frame and 100 through an aperture in these laterally projecting portions.

These portions 16 are provided with a plurality of slotted apertures 18—18, one of which is arranged in alignment with one of 105 the apertures 19—19 provided in the bag frame. When the parts are arranged as above outlined the tongue 20 of one of the elements 17 is passed through the aperture in the frame and through that particular 110 slotted aperture 19 which is in alignment therewith, and then bent to bind the arm to

the frame. The element 17 is provided with an enlarged portion 21 which may in one structure rest upon the uppermost face of the frame. This button or element 17 may 5 be composed of a substantially flat piece of material which is bent back upon itself as indicated at 22 and have the tongue 20 projecting therefrom, or it may also have its uppermost face curved to correspond to the 10 arc described by the swinging element 12. One or more of these buttons 17 may be slidably arranged in a casing 23 the latter of which may be adjusted with relation to the elements 17 to properly arrange it with respect to the hinged element 12, it being of course understood that the tongues such as 20 are passed through one of the slotted apertures in the lateral portions of the arms, and these tongues are subsequently bent to 15 clamp the parts together after the casing 23 has been adjusted relatively to the frame.

In this structure both the casing and the outermost part of the element 17 may be curved to correspond to the arc described 25 by the swinging member. This casing is preferably closed at its opposite ends and is further provided with the inwardly projecting flanges 24 upon which the elements 17 ride as the casing is shifted.

30 In the structure shown in Figure 7 the use of two telescopic elements 25 and 26 is contemplated, and each is provided with an extension 27 which is designed to be passed through an aperture in the frame. In the 35 particular arrangement shown the element 25 is provided with an inwardly projecting flange 28 and has its uppermost face curved as above outlined. The portion 26 is provided with the complementary part 29 which telescopes into the part 25. The edges 30 thereof ride upon the flange 28. This part 26 is further provided with a shoulder 31 which limits the movement of the part 25 towards the part 26, yet permits the parts to 40 be extended to compensate for various distances between the apertures in the frame.

The swinging element 12 is constructed to permit the handle to be arranged interiorly and exteriorly of the bag or bag frame, and 50 is therefore provided with the portion 32 which swings over and below the bag frame to position the handle which is secured to this portion within and without the bag. This portion is preferably curved to correspond to the arc described by the swinging 55 member. This element 12 is further provided with the portion 33 and the shank portion 34, the latter of which cooperates with a resilient detent 35 provided upon the 60 arms 10 and 11 to hold the element 12 in a position in which the handle is arranged exteriorly of the bag, yet permits these portions to be readily disconnected so as to permit the handle to be arranged within 65 the bag.

The portion 32 is provided with the loop 36 whereby the ring usually provided upon the end of a bag handle may be attached to the swinging member, this part being punched or otherwise formed of the material 70 of which the portion 32 is formed.

From the foregoing description it is evident that an arrangement is provided whereby a fitting may be secured to a bag frame, regardless of the relative distances between 75 the apertures in the frame. This permits one fitting to be substituted for another without demanding several fittings, each of which corresponds to the distance between the apertures provided in the various 80 frames.

Having described the invention, what I claim and desire to cover by Letters Patent is:

1. In a device of the class described, the combination of a member to which a bag handle is adapted to be secured, said member being adapted to be attached to another member, means for securing both of said members together, one of said members being adapted to be positioned relatively to the other to permit said securing means to engage and hold said last mentioned member in relatively different positions with respect to the other member. 95

2. In a device of the class described, the combination of a member to which a bag handle is adapted to be secured, said member being adapted to be attached to another member, means for securing both of said members together, said member to which the bag handle is secured being adapted to be positioned relatively to the other to permit said securing means to engage and hold said last mentioned member in relatively 100 different positions with respect to the other member. 105

3. In a device of the class described, the combination of a member to which a bag handle is adapted to be secured, said member being adapted to be attached to another member, means for securing both of said members together, one of said members being adapted to be positioned relatively to the other and relatively to the securing means to permit said securing means to engage and hold said last mentioned member in relatively different positions with respect to the other member. 115

4. In a device of the class described, the combination of a member to which a bag handle is adapted to be secured, said member being permitted to be attached to another member, means for securing both of said members together, said member to which the handle is secured having means permitting it to be positioned relatively to the other member, and to the securing means to permit said securing means to engage and hold said last mentioned member 125 130

in relatively different positions with respect to the other member.

5. In a device of the class described, the combination of a member to which a bag handle is adapted to be secured, said member being permitted to be attached to another member, means for securing both of said members together, said member to which the handle is secured having means permitting it to be positioned relatively to the other member to permit said securing means to engage and hold said last mentioned member in relatively different positions with respect to the other member, the means of the member to which the handle is secured including a plurality of separated elements engageable by the holding means.

6. In a device of the class described, the combination of a member to which a bag handle is adapted to be secured, said member being permitted to be attached to another member, means for securing both of said members together, said member to which the handle is secured having means permitting it to be positioned relatively to the other member to permit said securing means to engage and hold said last mentioned member in relatively different positions with respect to the other member, the means of the member to which the handle is secured including a plurality of separated elements between which said holding means is permitted to be passed to secure said members together.

35 7. In a device of the class described, the combination of a bag frame having an aperture, means having a handle secured thereto and securing means whereby the means having the handle and the frame may be secured together, said securing means including means which is adjustable relatively to the frame and having a portion which is passed through said aperture in the bag frame and into engagement with the means having the handle.

8. In a device of the class described, the combination of a bag frame, means having a handle secured thereto and means for securing the means having the handle to the frame, said means having the handle having an aperture permitting its adjustment relatively to the frame.

50 9. In a device of the class described, the combination of a bag frame, means having a handle secured thereto and means for securing the means having the handle to the frame, said means having the handle being apertured to permit of its adjustment relatively to the frame and the securing means.

60 10. In a device of the class described, the combination of a bag frame, means having a handle secured thereto and means for securing the means having the handle to the frame, said means having the handle

being apertured to permit of its adjustment relatively to the securing means.

11. In a device of the class described, the combination of a bag frame, means having a handle secured thereto and means for securing the means having the handle to the frame, said means having the handle being apertured to permit of its adjustment relatively to the securing means and the frame.

75 12. In a device of the class described, the combination of a bag frame, a member having a handle secured thereto, means for securing said member having the handle to the frame, said member being provided with a series of slotted apertures through which said securing means is passed, said apertures permitting said member having the handle to be adjusted and said securing means providing a means for holding said member having the handle with relation to the frame.

13. In a device of the class described, the combination of a bag frame and means having a handle secured to the frame, said means permitting the handle to be arranged upon opposite sides of the frame and means whereby said means having the handle may be arranged and releasably held outside of the bag when the bag is in an open condition.

85 14. In a device of the class described, the combination of a bag frame and means having a handle secured to the frame, said means permitting the handle to be arranged upon opposite sides of the frame and means for releasably holding said first mentioned means against movement with respect to the bag frame.

90 15. In a device of the class described, the combination of a bag frame and means having a handle, said means being secured to the frame and permitting said handle to be arranged upon opposite sides of the frame, said means being adjustable relatively to the frame and means for releasably holding the first mentioned means against moving toward the interior of the bag when the bag is open.

105 16. In a device of the class described, the combination of a bag frame and means having a handle, said means being secured to the frame and permitting said handle to be arranged upon opposite sides of the frame, means whereby said means may be moved and held relatively to the frame, said means including a member which is passed through the frame and through a portion of the means having the handle, and means for positively holding the means having the handle outside of the bag when the bag is opened.

110 17. In a device of the class described, the combination of a bag frame and means having a handle, said means being secured to

the frame and permitting said handle to be arranged upon opposite sides of the frame, means whereby said means having the handle may be adjusted longitudinally 5 of and held relatively to the frame, said means including a plurality of apertures and a member arranged upon one side of the frame and having means constructed to extend beyond the opposite sides of the 10 frame through an aperture and into engagement with the first mentioned means.

18. In a device of the class described, the combination of a bag frame and means having a handle, said means being secured to

the frame and permitting the handle to 15 be arranged upon opposite sides of the frame, means for securing said first mentioned means with relation to the frame, said securing means including an element 20 which is movable relatively to the means having the handle to permit the movable member to be brought into alignment with the means having the handle.

In witness whereof, I hereunto subscribe my name this 27th day of November A. D., 25 1920.

HENRY J. CHILTON.
